(57) **CLAIM**

The ornamental design for a cart for large area objects, as shown and described.

DESCRIPTION

FIG. 1 is a right side elevation view of a cart for large area objects showing our new design;

FIG. 2 is a left side elevation view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a rear perspective view thereof; and,

FIG. 8 is a front perspective view thereof.

Broken dash lines showing other elements of a cart are for illustrative purposes only and form no part of the claimed design.

1 Claim, 8 Drawing Sheets
